DES. 2179

John Arms, of Lansingburgh, New York.

Letter Patent No. 2179-Dated Oct. 10-1865.

Design for a Trade-Mark.

The schedule referred to in this Letter Patent and making part of the same.

To all whom it may concern:

Be it known that I, John Arms, of Lansingburgh, in the County of Albany, and State of New York have invented a new and useful Improvement in Design for a Trade-Mark, and I do hereby declare that the following is a full, clear and exact description thereof, which will enable others skilled in the art to make and use the same, reference being had to the accompanying drawings, forming part of this specification:

The drawing consisting of only one figure, represents my improved design applied to the handle of a brush.

The object of this invention is to produce a design for a trade mark to be applied to brushes.

In the drawing my design is shown applied to the handle of a hair brush, and said design consists in an outer ring A and an inner ring C, the space within the inner ring being occupied by a star, and the space between the two rings being marked with dots, and also having on its right hand side the representation of a bow-knot which projects a little way beyond the outer ring.

DES. 2179

2

Having thus described my invention, claim as my
and desire to secure by Letters Patent.

The design above described as a trade mark to brother
the above specification of my invention signed by
me this 16th day of June 1865.
